UNITED STATES PATENT OFFICE.

EDMOND CHARTON AND PIERRE MAURICE MONGEREAU, OF PARIS, FRANCE.

PULVERIZING MACHINE.

Application filed November 26, 1923, Serial No. 676,894, and in Belgium October 25, 1923.

This invention relates to pulverizing machines and has for its principal object so to construct such machines that they respond more fully to practical requirements than 5 has hitherto been the case.

The machine is of the type in which the fragments to be broken or disintegrated and pulverized are treated by means of percussion so that they are thrown against appropriate parts of the said machine.

According to the general principle of the invention, in constructing a machine of the class in question a concave or dished member is provided or a plurality of such members, each of which is provided around its periphery with vanes, so that each of these members acts as a centrifugal fan. Where a plurality of these members is provided, the various members are arranged concentrically and are rotated alternately in opposite directions.

A beater provided with blades which also constitutes a fan or ventilator is located on the interior of the first or innermost dished member and is rotated in an opposite direction to the said member.

In addition to the foregoing principal arrangement, the invention comprises certain other arrangements which are preferably 30 employed at the same time and which will be described more fully hereafter.

Amongst these may be mentioned the following:

A supplementary mechanism or apparatus 35 through which the air and pulverized materials issuing from the pulverizing machine are passed. This apparatus comprises a telescopic tube from the extremity of which the products reduced to the desired degree of 40 fineness determined by the height of the said tube are collected. These products which are as just mentioned of a greater or lesser degree of fineness fall into a collecting device, whilst those which are too heavy 45 fall back before reaching the end of the tube and are taken back to be retreated.

According to a further arrangement the machine is provided with a double jacket or casing and a fluid at an appropriate temperature which varies according to the products to be pulverized is caused to circulate 50 through the jacket or casing.

The invention also includes certain constructional embodiments which will now be 55 described with reference to the accompanying drawings, but it is to be understood that

the description and drawings are given merely by way of example.

Fig. 1 of the drawings shows in vertical axial section a pulverizing machine constructed according to a first method of carrying out the invention.

Figs. 2 and 3 show respectively in the same manner as Fig. 1 a detail of a pulverizing machine constructed according to a second 65 and a third method of carrying out the invention.

Fig. 4 shows in diagrammatic sectional elevation a pulverizing machine provided with means for separating the product according to fineness.

The pulverizing machine and associated apparatus according to the invention is constructed substantially as follows:

a is a rotary beater provided with blades 75 and forming a ventilator or fan, mounted at the end of a shaft *b*.

c is a concave or dished member embracing the beater *a* and also mounted at the end of a shaft *d*, which shaft is in alignment with 80 the shaft *b* and adapted to turn in the opposite direction thereto. The dished member is provided on the interior and on the exterior with radial vanes *e* so that it forms a centrifugal ventilator or fan.

f is a casing containing the whole mechanism and provided with a charging hopper *f^o*. *f^o* is another hopper which may be termed the "regulating hopper". *f^oo* is an exit orifice which may open radially with 90 respect to the member *c* or may be tangential thereto. The casing *f* may be formed with double walls so that a fluid circulation at a temperature appropriate to the nature and condition of the material being treated 95 can be passed therethrough. It may have on the interior a channelled surface which may be formed from a cylindrical plate *g* held in position in grooves *f¹* in the casing.

The vanes or blades of the beater and of 100 the dished or hollow member may be so formed, as also the dished member itself, that the conditions are the most suitable for the material to be treated.

For instance the construction illustrated 105 at Fig. 1 is one suitable for heavy and dry materials. The construction shown at Fig. 2 is for light and dry materials; whilst the construction indicated at Fig. 3 is for damp materials.

The machine is provided with means for collecting the pulverized products when re-

duced to the desired degree of fineness, and for returning to the said machine for further treatment those fragments which have not been reduced to the desired degree of fineness.

The apparatus in question is preferably constructed as follows:—

h is a chamber mounted above the exit orifice f⁰⁰ of the machine and provided with 10 a conduit h¹ communicating with the regulating hopper f⁰⁰. It is also provided with an inner lip or baffle h² which is formed from an inclined plate. The conduit h¹ is provided with a pivoted flap h³ which is 15 kept normally closed by an adjustable counterbalance weight, but which opens under the weight of material accumulating above it.

A system of telescoping tubes is also provided located above the chamber h. This system may comprise for instance two or more tubes such as i¹, i² . . . which are adapted to slide or telescope into one another, the action being controlled by suitable mechanism, as for instance by a rack j and a pinion in connection with a handle k.

l is a reservoir or receptacle provided with means at the bottom for facilitating the distribution of the pulverized products.

30 Into the upper portion of the said reservoir or receptacle opens the telescoping system of tubes. The reservoir communicates by a conduit m with the hopper f⁰⁰, with the interposition of a regulating flap or shutter n by means of which the section for the passage of air can be varied at will. The conduit m may comprise at any desired point, for instance at the highest point, means for admitting additional air.

40 By the foregoing construction an apparatus is produced, which functions in the following manner:—

The material to be pulverized is fed through the hopper f⁰⁰. The shafts b and d are rotated in opposite directions. The fragments to be disintegrated are carried along by the current of air produced by the blades a and they are thrown against the dished member c. They are caught up 50 by the current of air produced by the vanes e and are thrown against the channelled wall g. They are broken up into smaller pieces by reason of these successive impacts and are finally drawn away by the current 55 of air escaping through the orifice f⁰⁰.

By reason of the circulation of a hot or cold fluid through the double walls of the casing, where such circulation is provided, the materials may be treated in a special 60 manner and may be exposed to a temperature which is the most favourable for their disintegration.

The fragments which have been reduced to a sufficiently fine state are carried along 65 by the current of air to the reservoir, no

horizontal passages being present which would be undesirable and lead to the deposit of the material.

The heavier material which is still larger than required falls back down the tubes i¹ 70 and i², and being intercepted by the lip h² passes to the regulating hopper f⁰⁰ after causing the flap h³ to tilt. The air returns to the same hopper through the conduit m, 75 through the regulating shutter n which enables the current of air to be regulated and consequently the fineness of the product.

Moreover the telescoping system permits the height of the opening of the tube i² above the machine to be varied and to be adapted according to the weight of the fragments to be collected, that is to say in relation to the fineness of the resulting product, and also with relation to the density or the hygrometric state of the initial material.

As will be clearly understood, and as has already been stated, the invention is not limited in any way to the constructional embodiments or to the arrangements which have been more fully described. It includes 90 all modifications coming within a fair interpretation of the claims.

What we claim and desire to secure by Letters Patent of the United States of America is:—

1. In a pulverizing machine, the combination of a casing, having an inlet opening and an outlet opening, two shafts in alignment adapted to be driven in opposite directions and passing through bearings into the said casing, a beater provided with blades mounted on the end of one of the said shafts and within the said casing, and a dished member adapted partly to embrace the said beater and provided with radial 100 vanes mounted opposite to the said beater and on the end of the other shaft within the casing, said dished member having an annular projection extending over the blades of the said beater.

2. A pulverizing machine according to claim 1 having vanes mounted upon the said annular projection thereof, the said vanes being adapted to cause a centrifugal movement of the air in the casing when the said machine is operated.

3. A pulverizing machine according to claim 1 in which the said dished member has vanes mounted upon the said annular projection and also has vanes mounted interior to said annular projection whereby the said interior and exterior vanes impart a centrifugal movement to the air in the said casing when the said machine is operated.

In testimony whereof we have hereunto set our hands.

EDMOND CHARTON.

PIERRE MAURICE MONGEREAU.
